UNITED STATES PATENT OFFICE.

DAVID STOLL, OF NEW YORK, N. Y.

DESIGN FOR A METAL BORDER STRIP OR SIMILAR ARTICLE OF MANUFACTURE.

Application filed July 22, 1922. Serial No. 3,174. Term of patent 3½ years.

To all whom it may concern:

Be it known that I, DAVID STOLL, a citizen of the United States, and resident of the city of New York, in the county of Kings and State of New York, have invented a new, original, and ornamental Design for Metal Border Strip or Similar Article of Manufacture, of which the following is a specification, reference being had to the accompanying drawing, forming part thereof.

The figure is a top plan view of a portion of a border strip manufactured separately and suitable for attachment to silver plated

articles for forming an ornamental border at any point on the surface of said articles.

The design appears largely in relief and partly in intaglio on the wide surface of the metal strip.

I claim:

The ornamental design for a metal border strip or similar article of manufacture as shown and described.

Signed at the city of New York, in the county of New York, and State of New York, this 21st day of July, 1922.

DAVID STOLL.
